UNITED STATES PATENT OFFICE.

JOHN BRUSH, OF ALBANY, OREGON.

GRAIN-SEPARATOR.

SPECIFICATION forming part of Letters Patent No. 254,270, dated February 28, 1892.

Application filed July 22, 1891. (Model.)

To all whom it may concern:

Be it known that I, JOHN BRUSH, of the city of Albany, in the county of Linn and State of Oregon, have invented a new and useful Improvement in Grain-Separators, which improvement is fully set forth in the following specification, reference being had to the accompanying drawings, in which—

Figure 1 is a perspective view of my improved grain-separator. Fig. 2 is a longitudinal central section of the same, and Fig. 3 is a detail view.

My invention relates to improvements in grain-separators; and it consists in the peculiar arrangement and construction of the parts, as hereinafter more fully set forth.

In the accompanying drawings, *a* represents the frame of my improved grain-separator, which frame is of the usual construction and provided with a hopper and a fan, *b*, having a pinion, *c*, on its axle, which engages with a larger pinion, *d*, on a crank-shaft, *e*, journaled in one of the sides of the frame, whereby a rapid rotary motion is imparted to the fan.

To one end of the fan-shaft *e*, journaled in the sides of the frame, is secured a disk, *f*, provided with three or more holes, *g*, near its circumference, into one of which the bent end of the pitman *h* is inserted, the opposite bent end of the pitman *h* being inserted in one of a series of holes, *i*, in the outer arm of a bell-crank lever, *j*, journaled in angular brackets *k*, secured to one of the posts of the frame of the separator.

l represents an upper, and *l'* an under, shoe situated vertically below the upper shoe. The upper shoe, *l*, is suspended in the opening in the frame by the opposite hangers *l*¹ *l*², secured to the frame of the machine at their upper ends, and to the upper shoe, near its bottom, at their lower ends. Similar hangers are employed to suspend the upper shoe on its opposite side. The lower shoe, *l'*, is similarly suspended from each side of the frame by the hangers *l*³ *l*⁴.

m represents an angular plate secured to the upper shoe, *l*, near its bottom, and provided with a series of holes, *m'*, in its horizontal part.

n represents an angular plate secured to the lower shoe near its upper edge and immediately under the angular plate *m*. The angular plate *n* has its horizontal part provided with a series of holes, *n'*. The inner arm of the bell-

crank lever *j* is also provided with a series of holes, *i'*.

o o represent hooks, each bent at both ends and each adapted to engage in one of the holes in the inner arm of the bell-crank lever and in one of the holes in the angular plates *m n*, secured to the upper and lower shoes, whereby more or less transverse throw or oscillation may be imparted to either shoe, as desired, when the shoes are oscillated by turning the crank-shaft *e*.

p p are hooks bent at each end, the outer ends of the hooks being inserted in holes in lugs *p' p'*, attached to the opposite posts on each side of the frame, the inner ends of the hooks *p* being inserted in holes in lugs *p'' p''*, secured to the upper and lower shoe. Similar hooks are inserted in similarly-formed lugs in the opposite side of the machine.

q q represent lugs secured to the bottom of the upper shoe, *l*, on each side thereof, and projecting from the shoe laterally on each side thereof, and each provided with a hole for the passage of pins *r*, which pass thence into holes in the upper edges of the lower shoe, *l'*, thereby locking the shoes together, when desired.

The longitudinal sides of the upper shoe, *l*, are provided with opposite holes near their outer ends, through which passes a rod, *t*, screw-threaded at one end for the reception of a thumb-nut, *t'*, whereby the sides of the upper shoe may be clamped against the hurdle *u* when desired, and the inclination of the latter may be varied as desired. The inner faces of the longitudinal sides of the upper shoe, *l*, are provided with gains or grooves for the reception of riddles or sieve-frames when the hurdle is removed from the machine, as hereinafter described.

In separating oats from wheat or other grain the hurdle is introduced into the upper shoe and the proper inclination given it, when the hurdle is clamped in the upper shoe by the rod and thumb-nut. The hook coupling the inside arm of the bell-crank and the upper shoe is then inserted in the inside holes of the inner arm of the bell-crank and angular plate *m*, and the hook coupling the under shoe and bell-crank is inserted in the outside holes of the bell-crank and the angular plate secured to the lower shoe, whereby the upper shoe will have

less throw or vibration imparted to it than the lower shoe, which will have a longer vibration than the upper shoe.

For removing chaff from wheat or other grain the hurdle is removed and riddles or sieves inserted in the gains in the upper shoe, and the lower hook that connects the bell-crank lever with the lower shoe is removed, and also the two upper hooks that connect the upper shoe 10 on each side with the frame, and the two pins *r* that couple the shoes together are inserted, so that the two shoes form, in effect, a single shoe. The remaining hook coupling the shoes with the bell-crank lever may then be adjusted, as described, and the crank-shaft operated to winnow the grain.

What I claim as my invention is—

1. The combination, with the shoe *l*, frame *a*, and hangers *l' l'*, the shoe being provided 20 with the angular plate *m*, having a series of

adjusting-holes, *m'*, of the shoe *l'*, arranged under the shoe *l*, and hangers *l' l'*, the lower shoe being provided with angular plate *n*, having adjusting-holes *n'*, bell-crank lever *j*, provided with a series of adjusting-holes, coupling-hooks 25 *o*, and operating mechanism, substantially as described.

2. The combination, with the upper shoe, *l*, frame *a*, and hangers *l' l'*, the shoe being provided with the opposite perforated lugs *q*, of 30 the lower shoe, *l'*, lying under the shoe *l*, and provided with opposite holes in the upper edges of the sides, and pins *r*, substantially as described, and for the purpose set forth.

Albany, Oregon, January 4, A. D. 1881.

JOHN BRUSH.
